AUTOMATIC BRAKING DEVICE

Harry W. Allen, Dayton, Ohio

Application August 18, 1944, Serial No. 550,110

1 Claim. (Cl. 242—75)

(Granted under the act of March 3, 1883, as
amended April 30, 1928; 370 O. G. 757)

1

The invention described herein may be manufactured and used by or for the Government for governmental purposes, without the payment to me of any royalty thereon.

The invention to be hereinafter described relates to automatic brakes for reels.

There are a great number and variety of office machines for reeling tape or ribbon-type sheets from spool to spool across a plate or table for receiving or showing data of various kinds. The reeling or travel of the strip is intermittent, as is well understood, with frequent brief stops for one reason or another, according to the use of the machine. In order that the strip may be properly used whether for supplying data by being read or for receiving data, it should be maintained straight, flat and relatively taut or under suitable tension. In machines of this class, as heretofore built, there has been no simple and practical means or device for maintaining proper tautness or tension of the strip immediately following temporary stoppages. Instead, at every such stoppage there has been more or less over-run or unwinding from the delivery or supply roll with corresponding slack, looseness and lack of tension in the strip. The objects of the present invention are to overcome the above and other objections and provide a simple, efficient and compact device for automatically minimizing all such slackness and simultaneously taking up any slack not eliminated.

An important aim of the invention is to present an automatic brake device which is adapted to be produced at low cost, suitable for incorporation in conventional reeling and unreeling devices such as billing, order writing, manifolding machines and the like, without requiring extra space or special framing, by permitting its mounting upon usual side frame plates. It is also an aim to present such an automatic brake, which will be liable in a minimum degree to derangement or excessive wear in the use to be expected at sales counters, stock rooms and the like.

In order to more clearly disclose the construction, operation and use of the invention, reference should be had to the accompanying drawings forming part of the present application.

In the drawings:

Fig. 1 is an isometric perspective view showing the invention applied to a machine of the general character last mentioned above;

Fig. 2 is a left hand end view of Fig. 1 enlarged;

Fig. 3 is an enlarged fragmentary side elevation, with the near side plate removed, showing

the relative position of feed, idler and first guide rolls;

Fig. 4 is an enlarged diagrammatic view of the automatic brake mechanism in releasing position;

Fig. 5 is a like view in holding position; and

Fig. 6 is a detail of the idler roll mounting and cooperating trip.

It is not considered necessary or desirable to either illustrate or describe in any appreciable de-

tail the construction, operation or use of the machine on, to or with which this invention is applied. It may be any one of a wide range of standard and accepted machines in general use for reeling or winding strips or ribbons from a spool, reel or roll 3 at one end of the machine across over a table or plate 20 and onto another spool, reel or roll 2 at the opposite end. The spool axes are journaled in the frame X and slipped into and removed from place through slots 15, all in well known manner. The receiving roll 2 is driven through a suitable gear train 16 from a small motor device 17 with the usual stop-and-go switch 18 and speed control, not shown, all as is well known. Transverse horizontal guide rolls 25 21 are mounted at each end of the frame near, and at the level of, the table plate 20.

In Figs. 3, 4 and 5, particularly, the construction, arrangement and application of the invention in such machines is clearly illustrated.

30 In the well known type of reeling machine used to illustrate the invention, the record tape, strip, sheet, web or ribbon 1, reeled on the receiving roll 2 is unreeled or delivered from feed roll 3. From roll 3 the tape is looped rearwardly down, behind, under around and upwardly from an idler roll 4 journaled in the outer swinging ends of the brake releasing side arms of a pivotally mounted or swinging U-yoke or frame 5. While this is the preferred construction, it will be understood that a single, or parallel separate arms or parallel connected arms may be used to carry the roll 4. From each side arm of the yoke or frame 5, at or near the lower pivoted end, extends a short stub shaft or pivot 6 by which the 45 U-yoke is pivotally journaled in the respective side wall X of the machine. These pivots are close to the vertical plane of the shaft 19 of the roll 3, and the frame 5 swings freely back and forth across this plane below the roll 3 and its web load. Fixed to and movable with each pivot 6 (and consequently fixed with the arms at 5) there is a short foot or lift cam or crank arm 7, for a purpose to be later disclosed. As shown in the drawings (particularly Figs. 3, 4 and 5), arm 7 with yoke 5 and pivot 6 present substan-

tially a bell crank lever. The short arm 7 of this bell crank is positioned to engage under a vertically extending brake bar 8 slidably mounted on the respective side wall of the machine and having an upper end broadened and punched out to form a shoe yoke 9 which fits about and tends to move downward and frictionally engage a brake drum 10 fixed on the respective end of the shaft 19 keyed to the feed roll 3. To develop therein appreciable braking force, a spring 11 is used, mounted on the wall X and having an end pressing downward on a pin set in the side of the bar 8. As the tape, ribbon or the like is drawn toward the receiving roll 2 when the motor operates the latter, it will swing the idler 4 toward the receiving roll 2, as shown in Fig. 4. In that position, as shown, foot 7 lifts bar 8 so that its yoke 9 is clear of drum 10, permitting free running feeding action of roll 3. On sudden stoppage, tension on the strip or ribbon is removed and spring 11 forces brake bar 8 down, causing downward swing of foot 7 with corresponding rocking of U-yoke 5 generally from the direction of the roll 2 toward roll 3, the idler 4 thereby taking up any momentary slack in the tape. As this operation takes place the brake yoke 9 seats in the grooved surface of the brake drum 10 and spring 11 applies braking pressure preventing any further momentary unwinding from roll 3. On the other hand, as the motor starts again and reeling begins, the tension on the tape draws idler 4 toward roll 2, lifting bar 8 and shoe 9 against the action of spring 11. This allows the slack in web 1 to be reeled in, and frees the drum 10 to again permit free running feed of tape from roll 3.

Suitable guides 22 such as straps, pin-and-slot or the like, of well known construction and arrangement, may be used to assure properly aligned travel of the bar 8 and yoke 9 in their operation. Likewise, to minimize friction, the cooperating contacting surfaces of 7 and 8 are adequately curved or rounded as shown. The parts 6 to 11, inclusive, at one side of the machine are duplicated at the opposite side. Description of those at one side equally describes those at the other side.

The whole brake operation is automatic, both as to applying and as to releasing. As the reeling tension starts the brake automatically releases and as the reeling tension stops the brake is automatically applied.

It is thought that the construction, operation and use of the invention will be clear from the preceding detailed description.

Many changes may be made in the construction, arrangement and disposition of the parts of the invention within the scope of the appended claim without departing from the field of the invention and it is meant to include all such within this application wherein only one preferred form has been illustrated purely by way of example.

Having thus described my invention, what I claim and desire to protect by Letters Patent is:

An automatic brake for intermittent web unreeling rolls comprising a rotatable reel shaft, a reel fixed on the shaft, a support therefor, a brake drum on the shaft, an elongated brake bar slidably longitudinally on said support radially in relation to the drum and having its medial line arranged in a radial plane of the shaft and drum, a shoe yoke formed on the bar having an opening therein receiving the said drum loosely therewithin, said opening being elongated in the direction of sliding movement of the bar to clear the drum at times, resilient means coengaged between the support and brake bar tending to apply the shoe to the drum in one direction of sliding movement of the bar, a brake release arm pivoted a distance from said shaft and closely adjacent said radial plane of the shaft, the free end of the arm being toward the shaft and movable toward and from said plane between the shaft and the pivot of the arm, an idler roll carried by the free part of the brake release arm positioned to receive therearound a loop of web when such loop is extended from said reel generally at a substantial angle across said plane, and a crank arm fixed with the release arm engaged across and bearing on a part of the brake bar; said crank arm extending from the release arm in a direction to move the bar against action of said resilient means under pull of a web loop engaged around said idler.

Certificate of Correction

Patent No. 2,438,887.

April 6, 1948.

HARRY W. ALLEN

It is hereby certified that errors appear in the above numbered patent requiring correction as follows: In the grant, lines 1 and 13, name of inventor, for "Henry W. Allen" read *Harry W. Allen*; and that the said Letters Patent should be read with these corrections therein that the same may conform to the record of the case in the Patent Office.

Signed and sealed this 1st day of June, A. D. 1948.
